SMUDGE POT IGNITER

Sydney R. Crockett, Freeport, N. Y., assignor to
Cyril Charles Crockett, Glendale, Calif.

Application December 28, 1946, Serial No. 719,097

13. Claims. (Cl. 67—3)

1

The object of this invention is to provide an automatic smudge pot igniter. The use and operation of smudge pots for raising the temperature in citrus fruit groves are too well known to require any extended explanation. So far as I know the ignition or lighting of smudge pots requires much manual labor and constant vigilance in observing atmospheric temperature changes in order that the smudge pots may be ignited at the proper time to save the crop.

The invention is embodied in a smudge pot igniter in which a flame is produced automatically in order to ignite the wick in the smudge pot. The flame results from the coaction of certain chemicals which are brought together in a cartridge which is inserted in the smudge pot in contact with the wick therein. Certain chemicals, for example, chromic anhydride, iodine crystals and potassium nitrate are compounded to form an ignition tablet which is placed in the cartridge on a porous ceramic base. When the temperature in the field is lowered below a selected critical point, another chemical, for example, isopropyl alcohol, is brought into contact with the said tablet with the result that an instantaneous flame is produced which will continue to burn as long as the alcohol capacity lasts. The flame ignites the oil wick in the smudge pot to produce a smudge fire.

An important feature of the invention is a temperature controlled valve mechanism which is normally closed to cut off the supply of alcohol from reaching the cartridge tablet. The valve mechanism is arranged to open when a given low temperature is reached. The valve mechanism has two main parts, namely a spring closed valve which is movable in one direction due to the contraction of the isopropyl alcohol below a given temperature and valve releasing means which is movable in the opposite direction due to the expansion of distilled water. When the two parts of the valve mechanism meet, the valve is opened and the alcohol then flows to contact the chemical ignition tablet.

The alcohol is contained in an expansion tube and as the tube expands and contracts the valve which is secured to the tube moves therewith. Likewise, distilled water is contained in a sealed tube capable of expansion and contraction and the valve releasing means which is secured to the water tube moves therewith.

The detailed description of the igniter according to this invention is set forth in the following specification and illustrated in the accompanying drawing in which

2

Fig. 1 is a sketch illustrating the use of the invention.

Fig. 2 is a central vertical sectional view through the igniter, with parts broken away.

Fig. 3 is an outside view with parts removed.

Fig. 4 is a cross sectional view of the igniter taken on the line 4—4 of Fig. 2.

Fig. 5 is a top plan view.

Referring first to Fig. 1, the reference numeral 10 denotes the valve operating unit. The numeral 11 marks the valve unit and the numeral 12 denotes the igniter cartridge. The latter is inserted within the smudge pot 9 to ignite the wick 10 therein, and the wick in turn ignites the oil 11. A clip 12 or other suitable means may be used to support the device on the smudge pot.

Referring now to Fig. 2, the valve operating unit 10 consists of an expansion tube 13 secured at the top to a disk 14 having a key 15. The bottom of the tube 13 is open and carries a nipple 16 to which is attached a capillary valve tube 17 of special neoprene rubber, or other suitable valve material. To the bottom of the rubber tube there is attached a bendable pipe 18. The rubber tube acts as a valve and is shown collapsed as at 19 by means of springs 19, 19 which extend downward from a spring member 20.

The outer end of the pipe 18 carries a threaded coupling 21 for securing the igniter cartridge to the pipe. The cartridge contains an igniter tablet 22 consisting of certain compounded chemicals, for example, 55 parts of chromic anhydride, 20 parts of iodine crystals and 5 parts of potassium nitrate. This compound has the property of producing a flame when contacted by isopropyl alcohol which is contained within the tube 13. The compound is contained within a porous ceramic base or cup 23 from which a nipple 24 may project to be secured by the coupling 21 to the pipe 18. There is an air space 25 between the tablet 22 and the ceramic base and the nipple 24 has openings 26 providing communication between the air space and the pipe 18. A coating 27 of paraffin or like substance encloses the cartridge as shown to prevent moisture from contacting the tablet and impair the potency thereof. When the valve 16 is opened there is an unobstructed passage from the alcohol tube 13 to the tablet 22.

The tube 13 is surrounded by an outer double walled expansion tube 30 having the inner wall 31 and an outer wall 32 forming an annular chamber 33 which contains distilled water and is sealed. At the top the tube 30 carries a cover 34 which

is rotatable upon the disk 14 and suitably retained therewith. The cover 34 has an opening 35 through which the key 15 projects. The cover 34 has two stops 36 and 37, see Fig. 5.

The bottom of the tube 30 carries a valve release casing 38 which surrounds the springs 19. The ends of the springs engage the inner wall of the casing under spring pressure. A spring tension adjusting nut 40 is screwed into the valve casing and the ends of the springs rest upon the upper edge of the nut as shown. The valve release casing 38 has two openings 42, 42 which are normally in vertical alignment with the springs 19. However, by turning the tube 13 by means of the key 15 from the "on" position against the stop 36 to the "off" position against the stop 37, the springs 19 and the openings 42 are no longer aligned vertically.

The two tubes 13 and 30 are capable of expansion and contraction at atmospheric conditions. They are of very thin metal, approximately .005 inch thick and are therefore illustrated by a single line, not sectioned. They have an expansion quality consistently uniform over a given linear measurement. The corrugations are very large in proportion to the lengths of the tubes. The tube 30 is filled with highly distilled water under pressure and is then sealed. The tube 13 is filled with isopropyl alcohol under about three pounds pressure. The cubic capacity of the tube 13 is approximately three quarters of the capacity of the tube 30 because the coefficient of expansion of isopropyl alcohol is approximately one and one half times greater than that of water.

Throughout a temperature range of plus 150 degrees F. to minus 45 degrees F., isopropyl alcohol has a consistent and uniform curve as far as the expansion and contraction characteristics thereof are concerned. Isopropyl alcohol expands .00109 cubic centimeter per degree temperature change using as a basic measure one cubic centimeter. Water has a uniform expansion and contraction curve from plus 150 degrees F. and until it reaches plus 39.2 degrees F. At this point water has the unusual characteristic of expansion at the rate of .00002 cubic centimeter per one degree F. minus. At 32 degrees F. zero centigrade, water has expanded .00014 cubic centimeter for every cubic centimeter of water within the tube 30. At the critical point of 39.2 degrees F. the tube 13 which contains the isopropyl alcohol continues to contract below this temperature and the tube 30 which contains distilled water continues to expand. The lower ends of the two tubes therefore move in opposite directions with relation to one another and these movements are utilized to operate the valve.

At any given temperature below 39.2 degrees F. the valve 16 with the valve closing springs 19 moves upward, whereas the valve release casing 38 with the openings 42 moves downward. As a result of these two opposed movements, the springs and the openings will become horizontally aligned. The springs will snap outward through the openings and the valve 16 will open, the neoprene rubber tube tending to assume its normal tubular form. By adjusting the nut 40 the said two valve elements may be caused to meet at any given temperature at which the valve is to be opened. As a result, the isopropyl alcohol will flow out through the pipe 17 under pressure into contact with the ignition tablet 22 and the resulting flame will be produced to ignite the smudge pot as will be understood.

When the alcohol reaches the tablet and spreads over the highly evaporative porous ceramic base an instantaneous flame results from the chemical reaction between the isopropyl alcohol and the compounded chemical tablet.

The flame will continue to burn as long as the alcohol capacity lasts. The ignited alcohol will be dispersed over the oil saturated wick in the smudge pot and the oil therein will be ignited to produce a smudge fire.

During transport or storage the key 15 will be turned to "off" position to prevent opening of the valve. The key will be turned to "on" position when the igniter is attached to the smudge pot. The igniter cartridge is inserted within the pot in close contact with the oil wick. The bendable pipe 17 facilitates the work of attaching the igniter and pressing the cartridge into contact with the wick. A clip or wire 12 or any other suitable means may be used to attach the igniter to the pot.

While the igniter is attached to the smudge pot, the two expansion tubes 13 and 30 will continue to expand and contract in response to atmospheric temperature variations and the bottoms of the tubes will move in the same general direction toward the cartridge. When a predetermined critical degree of temperature is reached, the two tubes will have expanded and contracted, respectively, to such an extent that the valve opens automatically. The cartridge becomes a ball of fire and is eventually consumed.

The use of the igniter according to this invention relieves the farmer from the tedious job of watching the temperature and the manual labor of lighting the smudge pots. The chemicals named above, their proportions and properties are by way of example only and not to be taken as limitations in the scope of this invention.

I claim:

1. A smudge pot igniter comprising a cartridge for igniting the wick in a smudge pot, said cartridge containing a chemical compound capable of producing a flame by contact with isopropyl alcohol, an expansion tube containing isopropyl alcohol, one end of said tube being closed, a sealed expansion tube containing distilled water, means connecting and supporting said tubes at one end thereof to afford individual expansion and contraction at the opposite ends of said tubes, a valve secured to the open end of said isopropyl alcohol tube and movable with said tube as it expands and contracts, means on said valve for normally closing the same, an alcohol conducting pipe connected between said valve and said cartridge compound, valve releasing means secured to said sealed water tube to move therewith as said water tube expands and contracts, said tubes being capable of expansion and contraction in response to atmospheric temperature, means for supporting said valve releasing means in spaced relation to the valve closing means to prevent opening of the valve during expansion and contraction of the said two tubes above a predetermined temperature, said valve closing and valve releasing means being brought into valve opening relation to open the valve by the relative contraction and expansion of said expansion tubes when said predetermined temperature has been reached and the isopropyl alcohol is to be conducted to the chemical compound in the said cartridge to produce a flame to ignite the wick in the smudge pot.

2. A chemical compound according to claim 1 consisting of chromic anhydride, iodine crystals and potassium nitrate approximately in the proportions of 55 parts anhydride, 20 parts iodine crystals and 5 parts of potassium nitrate.

3. An automatic liquid discharge device comprising: a pair of resilient expandible shells secured together at one end; a body of liquid substantially entirely filling each shell, at least one of said liquid bodies maintaining the containing shell tensioned, said liquids having different coefficients of expansion; said containing shell having an outlet; valve means carried by said shell at the unsecured end, controlling said outlet, and having a control member; and an operating member carried by the unsecured end of the other shell, normally maintaining said control member in outlet closing position, and operating said control member to open the outlet upon relative movement between said members caused by a change in volume of the said liquids responsive to a predetermined ambient temperature.

4. An automatic liquid discharge device comprising: a pair of resilient expandible shells secured together at one end; a body of liquid substantially entirely filling each shell, at least one of said liquid bodies maintaining the containing shell tensioned; said containing shell having an outlet; one of said liquids having a volume varying consistently with temperature, the other liquid having a volume increasing with falling temperature over a limited range; valve means carried by said shell at the unsecured end, controlling said outlet and having a control member; and an operating member carried by the unsecured end of the other shell, normally maintaining said control member in outlet closing position, and operating said control member to open the outlet upon relative movement between said members caused by a change in volume of the said liquids responsive to a predetermined ambient temperature.

5. An automatic liquid discharge device comprising a pair of resilient expandible shells secured together at one end; a body of liquid substantially entirely filling each shell, at least one of said liquid bodies maintaining the containing shell tensioned; said containing shell having an outlet; said liquids having different coefficients of expansion; valve means carried by said shell at the unsecured end, controlling said outlet and having a control member; an operating member carried by the unsecured end of the other shell, normally maintaining said control member in outlet closing position, and operating said control member to open the outlet upon relative movement between said members caused by a change in volume of the said liquids responsive to a predetermined ambient temperature; and means for adjusting the relative positions of said members to alter the temperature at which said outlet is opened.

6. An automatic liquid discharge device comprising: a pair of resilient expandible shells secured together at one end; a body of liquid substantially entirely filling each shell, at least one of said liquid bodies maintaining the containing shell tensioned; said containing shell having an outlet; one of said liquids having a volume varying consistently with temperature, the other liquid having a volume increasing with falling temperature over a limited range; valve means carried by said shell at the unsecured end, controlling the outlet and having a control member;

an operating member carried by the unsecured end of the other shell, normally maintaining said control member in outlet closing position, and operating said control member to open the outlet upon relative movement between said members caused by a change in volume of the said liquids responsive to a predetermined low temperature; and means for adjusting the relative positions of said members to alter the temperature at which said outlet is opened.

5 7. An automatic liquid discharge device comprising: a pair of resilient expandible shells secured together at one end; a body of liquid substantially entirely filling each shell, at least one of said liquid bodies maintaining the containing shell tensioned; said containing shell having an outlet; said liquids having different coefficients of expansion; valve means carried by said shell at the unsecured end, controlling the outlet and having a control member; an operating member carried by the unsecured end of the other shell, normally maintaining said control member in outlet closing position, and operating said control member to open the outlet upon relative movement between said members caused by a change in volume of the said liquids responsive to a predetermined ambient temperature; and means for optionally restricting relative movement between the members to prevent opening of said outlet.

10 8. An automatic liquid discharge device comprising: a pair of resilient expandible shells secured together at one end; a body of liquid substantially entirely filling each shell, at least one of said liquid bodies maintaining the containing shell tensioned; said containing shell having an outlet; one of said liquids having a volume varying consistently with temperature, the other liquid having a volume increasing with falling temperature over a limited range; valve means carried by said shell at the unsecured end, controlling the outlet and having a control member; an operating member carried by the unsecured end of the other shell, normally maintaining said control member in outlet closing position, and operating said control member to open the outlet upon relative movement between said members caused by a change in volume of the said liquids responsive to a predetermined ambient temperature; and means for optionally restricting relative movement between the members to prevent opening of said outlet.

15 9. An automatic liquid discharge device comprising: a pair of resilient expandible shells secured together at one end; a body of liquid substantially entirely filling each shell, at least one of said liquid bodies maintaining the containing shell tensioned; said containing shell having an outlet; one of said liquids having a volume varying consistently with temperature, the other liquid having a volume increasing with falling temperature over a limited range; valve means carried by said shell at the unsecured end, controlling the outlet and having a control member; an operating member carried by the unsecured end of the other shell, normally maintaining said control member in outlet closing position, and operating said control member to open the outlet upon relative movement between said members caused by a change in volume of the said liquids responsive to a predetermined low temperature; and means for optionally restricting relative movement between the members to prevent opening of said outlet.

20 10. An automatic igniter comprising a pair of resilient expandible shells; a body of liquid sub-

25 30 35 40 45 50 55 60 65 70

stantially entirely filling each shell, at least one of said liquid bodies maintaining the associated shell tensioned, said liquid body having a volume varying consistently with temperature throughout the range of operation of the igniter, the other body having a volume varying consistently with temperature only through a portion of said range; means connected to move with the end of one shell forming a valved outlet therefrom, comprising a spring finger for controlling the outlet, having an operating projection; a member connected to move with the end of the other shell; means joining the opposite ends of the shells against relative movement, said member normally engaging said projection and tensioning said finger to maintain the outlet closed, said member having an opening adapted to receive said projection and release said finger to cause opening of said outlet; the volumes of said liquids at a predetermined temperature being such as to position said projection to enter said opening, and cause the outlet to open; and means whereby said liquid when released produces flame.

11. An automatic igniter comprising a pair of resilient expansible shells; a body of liquid substantially entirely filling each shell, at least one of said liquid bodies maintaining the associated shell tensioned, said liquid body having a volume varying consistently with temperature throughout the range of operation of the igniter, the other body having a volume varying consistently with temperature only through a portion of said range; means connected to move with the end of one shell forming a valved outlet therefrom, comprising a spring finger for controlling the outlet, having an operating projection; a member connected to move with the end of the other shell; means joining the opposite ends of the shells against relative movement, said member normally engaging said projection and tensioning said finger to maintain the outlet closed, said member having an opening adapted to receive said projection and release said finger to cause opening of said outlet; the volumes of said liquids at a predetermined temperature being such as to position said projection to enter said opening and cause the outlet to open; means for adjusting the relative positions of said member and said finger to cause said projection to enter said opening at a different temperature; and means whereby said liquid when released produces flame.

12. An automatic igniter comprising a pair of resilient expansible shells; a body of liquid substantially entirely filling each shell, at least one of said liquid bodies maintaining the associated shell tensioned, said liquid body having a volume varying consistently with temperature throughout the range of operation of the igniter, the other body having a volume varying consistently with temperature only through a portion of said range; means connected to move with

the end of one shell forming a valved outlet therefrom, comprising a spring finger for controlling the outlet, having an operating projection; a member connected to move with the end of the other shell; means joining the opposite ends of the shells against relative movement, said member normally engaging said projection and tensioning said finger to maintain the outlet closed, said member having an opening adapted to receive said projection and release said finger to cause opening of said outlet; the volumes of said liquids at a predetermined temperature being such as to position said projection to enter said opening and cause the outlet to open; means for adjusting the relative positions of said member and said finger to misalign said opening and said projection to prevent opening of the outlet; and means whereby said liquid when released produces flame.

13. An automatic igniter comprising a pair of resilient expansible shells; a body of liquid substantially entirely filling each shell at least one of said liquid bodies maintaining the associated shell tensioned, said liquid body having a volume varying consistently with temperature throughout the range of operation of the igniter, the other body having a volume varying consistently with temperature only through a portion of said range; means connected to move with the end of one shell forming a valved outlet therefrom, comprising a spring finger for controlling the outlet, having an operating projection; a member connected to move with the end of the other shell; means joining the opposite ends of the shells against relative movement, said member normally engaging said projection and tensioning said finger to maintain the outlet closed, said member having an opening adapted to receive said projection and release said finger to cause opening of said outlet; the volumes of said liquids at a predetermined temperature being such as to position said projection to enter said opening and cause the outlet to open; means for adjusting the relative positions of said member and said finger in one direction to alter the temperature at which the outlet is opened, and in a direction transverse thereto to prevent opening of the outlet; and means whereby said liquid when released produces flame.
